UNITED STATES PATENT OFFICE.

JOSEPH REID, OF OIL CITY, PENNSYLVANIA.

WELL-DRILLING CABLE.

No. 826,063.

Specification of Letters Patent.

Patented July 17, 1906.

Application filed March 7, 1905. Serial No. 248,812.

To all whom it may concern:

Be it known that I, JOSEPH REID, a citizen of the United States, and a resident of Oil City, in the county of Venango, State of Pennsylvania, have invented certain new and useful Improvements in Well-Drilling Cables, of which the following is a specification.

It is generally well known that for successfully drilling deep wells the elasticity of the drilling-rope plays an important part in the stroke of the tool. Hemp ropes, however, which have the quality of elasticity, are undesirable for deep well-drilling for well-known reasons. It has been attempted to combine the hemp rope with a steel cable by splicing the steel cable to the hemp rope—that is to say, by weaving the strands of the steel cable over and under the strands of the hemp rope. This method is objectionable, because the joint is not durable, it being found that the steel strands soon cut the hemp strands and the wear on the splicing is excessive.

The object of my present invention is to produce a composite drilling-cable in which the connection between the two kinds of rope will be at least as strong and durable as the weaker and less durable of the two ropes to be joined.

In carrying out my invention I unlay a sufficient length of the hemp rope to provide the necessary length of connection and then hold the end of the wire rope centrally to the hemp rope and relay the strands of the hemp rope tightly and closely about the steel rope as a core or center, suitably secure the ends of the strands of the hemp rope, and clamp the splice or joint thus produced at suitable intervals by semicylindrical clamps held together by rivets passing through both the hemp and steel ropes without cutting or breaking the fiber or strands in either. The end of the steel rope is preferably tapered before being introduced into the hemp rope by removing a suitable number of the individual wires from its several strands, and the tapered end is wire wound or bound to prevent unraveling. The end is preferably provided with a further winding or binding below each rivet to prevent unlaying or unraveling of the strands of the wire rope under the pull of the through-rivet.

My invention will be fully understood upon reference to the accompanying drawings, in which—

Figure 1 is a view of the joint produced by my invention. Fig. 2 is a view of the two

ropes presented coaxially. Fig. 3 is a transverse section through one of the rivets. Fig. 4 is a longitudinal section through the end of the joint and its finishing-clamp.

60

A represents the joint to be formed, which consists of the central steel or wire rope core 1, the surrounding hemp rope 2 laid about the core, the clamps 3, 4, and 5 for securing the hemp rope to the steel core and preventing relative longitudinal movement between the parts.

In producing my improved well-drilling cable I take a suitable length of hemp rope, preferably hawser-laid, and unravel the ends, as shown at 2^a in Fig. 2. I then take a length of steel or wire cable which, with the length of Manila rope, will be sufficient for the drilling operations to be undertaken, and I taper the end of the steel rope, as shown at 1^a, by cutting back one or more of the wires on each strand, after which the tapered end is bound, as shown at 6, by means of a wire or by brazing or soldering. I also bind it, as shown at 7, at a point adjacent to the location of each rivet to be referred to.

70

75

80

In producing the improved splice the tapered end 1^a of the wire rope is drawn into the end of the rope 2 by the wires 10, the strands 2^a are twisted at the proper pitch to correspond to the angle of lay to be imparted to the strands, and said strands are laid about the steel-rope center. When a sufficient length of lay has been made, the joint is finished by applying the clamps 3, 4, and 5, which are secured by rivets passing through both the wire and manila ropes immediately above the windings 7 thereon, while clamp 5, being exteriorly threaded, receives a tapered sleeve 23, which has been passed over the end of the wire rope previous to the commencement of the operation of forming the splice. By means of this clamp 5 and threaded taper sleeve 23 the ends of the laid strands may be permanently secured and the desired taper finish be provided at the end of the splice.

85

90

95

100

A splice or joint produced as herein described will be as strong as the weaker of the two ropes. It will work satisfactorily over pulleys or guide-sheaves without producing undue wear on the parts, and there will be no cutting or undue wear upon the strands of the rope at the splice or elsewhere.

105

The terms "laid" or "laying" are used in this specification in their technical sense as understood by ropemakers—that is to say, to convey the idea of laying the strands of a

110

rope by twisting and spirally winding them. Thus the term "laid joint" conveys the idea of a joint formed by using one of the rope ends as a core and taking the unlaid strands of the other rope and twisting and winding them about said core or winding them while maintaining the twist that they have already received in the manufacture of the rope.

Having thus described my invention, the following is what I claim as new therein and desire to secure by Letters Patent:

1. A composite well-drilling cable, having its sections united by a laid joint.
2. A composite well-drilling cable having its sections united by a laid joint and clamps.
3. A composite well-drilling cable having its sections united by a laid joint and clamps with rivets passing through the ropes.
4. A composite rope having its sections united by laying the strands of the hemp rope around the wire rope and securing them by clamps.

5. A composite rope having the end of its steel rope wound or bound, and the strands of its hemp rope laid about said steel rope by twisting and winding, and secured thereon by a clamping - rivet passing diametrically through both ropes just above the binding on the steel rope.

6. A composite rope having the end of its wire section tapered and bound at the tapered end and above the same, and having the end of its hemp section unlaid, and the strands thereof tightly twisted and closely wound upon the steel section and secured thereto by clamps and diametric through-rivets.

The foregoing specification signed at Washington, District of Columbia, this 4th day of February, 1905.

JOSEPH REID.
